US00D927466S

(12) **United States Design Patent** (10) **Patent No.:** **US D927,466 S**
Zhang et al. (45) **Date of Patent:** **** Aug. 10, 2021**

(54) **PAIR OF BLUETOOTH EARPHONES**

(71) Applicant: **BEIJING XIAOMI MOBILE SOFTWARE CO., LTD.**, Beijing (CN)

(72) Inventors: **Lei Zhang**, Beijing (CN); **Ningning Li**, Beijing (CN); **Ziran Zhao**, Beijing (CN)

(73) Assignee: **BEIJING XIAOMI MOBILE SOFTWARE CO., LTD.**, Beijing (CN)

(**) Term: **15 Years**

(21) Appl. No.: **35/507,458**

(22) Filed: **Feb. 21, 2019**

(80) **Hague Agreement Data**

Int. Filing Date: **Feb. 21, 2019**

Int. Reg. No.: **DM/202815**

Int. Reg. Date: **Feb. 21, 2019**

Int. Reg. Pub. Date: **Sep. 20, 2019**

(30) **Foreign Application Priority Data**

Aug. 21, 2018 (CN) 201830463333.7

(51) **LOC (13) Cl.** **14-01**

(52) **U.S. Cl.**

USPC **D14/223**

(57) **CLAIM**

The ornamental design for a pair of Bluetooth earphones, as shown and described.

DESCRIPTION

- 1.1 : Front view of the first embodiment
1.2 : Back view thereof
1.3 : Left view thereof
1.4 : Top view thereof
1.5 : Bottom view thereof
1.6 : Front perspective view thereof
1.7 : Back perspective view thereof
(Continued)

- 1.8 : Front view of the second embodiment
 1.9 : Back view thereof
 1.10 : Left view thereof
 1.11 : Top view thereof
 1.12 : Bottom view thereof
 1.13 : Front perspective view thereof
 1.14 : Back perspective view thereof
